(57) **CLAIM**

The ornamental design for a handset, as shown and described.

DESCRIPTION

FIG. 1 is a perspective front view of a handset showing our new design;

FIG. 2 is a front view thereof;

FIG. 3 is a right side view thereof;

FIG. 4 is a left side view thereof;

FIG. 5 is a top view thereof;

FIG. 6 is a bottom view thereof; and,

FIG. 7 is a rear view thereof.

The broken lines that show the outermost periphery of non-claimed features represent boundaries of the claimed design. All other broken lines are directed to environment. The broken lines and unshaded regions that are defined by broken lines form no part of the claimed design.
